Gthys.

UNITED STATES PATENT OFFICE.

WILLIAM S. HAMM, OF HUBBARD WOODS, ILLINOIS, ASSIGNOR TO THE ADLAKE COMPANY, A CORPORATION OF ILLINOIS.

SIGNAL LANTERN.

Application filed July 16, 1926. Serial No. 122,882.

The invention relates to lanterns used in the railway service and especially by train and yard men. While such lanterns are required in the railway service for general illumination, their especial use is in the giving of signals for controlling the movement of trains. In the handling of the lantern in signaling, it is swung in various ways, is frequently brought to a horizontal position and 10 is sometimes actually inverted. It is subjected to winds of very high velocity especially when carried on top of a freight train which is running against a head wind, and among the most trying conditions are those 15 due to the movements of the user, as when jumping down from a car and running alongside of the track. It is, of course, essential that the light be dependable and its failures must be reduced to the lowest possible number. The difficulties in organizing 20 a lantern for this service have been increased by the recent adoption of a light fuel such as kerosene instead of the heavier so-called signal oil which had been employed for 25 many years. In the burning of kerosene, a copious supply of air is required yet the flame is very sensitive and must be protected against too violent air currents and from a reversal of the currents, which may be set 30 up from a variety of causes and which tends to smother the flame not only by cutting off the supply of oxygen but preventing the vapors of combustion from being carried away from the burner.

35 It is further important that the structure be simple, for the purpose of keeping its cost as low as possible and for the further purpose of convenience in its care.

The objects of the present invention are to 40 improve the bottom ventilation of such lanterns with view to provide an adequate supply of air to the burner while preventing its delivery in violent and flame disturbing currents, and furthermore to counteract the 45 tendency to a reversal of current especially when the lantern is subjected to violent jar- 50 ring as when the user jumps from the car to the ground, and to counteract what seems to be a pumping action produced by the up and down motion of the lantern as the user runs with it on the ground or on top of the train.

A further object is to simplify the lower portion of the lantern structure, reducing

the number of parts of which it is composed and conducing to simplicity of assembly. 55

These objects are obtained by, and the invention consists in the structure hereinafter described and illustrated in the accompanying drawings in which—

Figure 1 is a side elevation of the lantern, 60 partly in section and with some parts broken away, and

Fig. 2 is a detail section on line 2—2 of Fig. 1 some of the parts being omitted.

The lantern comprises the usual guard 65 frame 10 preferably of wire, a so-called base ring 11, and oil font 12, seated within the base ring, and globe 13, seated upon the base ring, and dome 14, and a globe holder 15 carried within the dome and spring pressed 70 downwardly against the top of the globe.

The globe holder is of any desirable form such as that shown in the Hamm & Schuetz Patent, No. 1,415,633 of May 9, 1922. The upper part of the lantern will, of course be 75 provided with suitable ventilating ports and with a bale by which it may be carried, but as the present invention is not concerned with these features of the lantern, they have been omitted from the drawings. 80

The lower portion of the base ring 11, is, as usual, of such diameter as to receive the font 12. Its upper portion 16 is offset outwardly to provide a passage 17 for air entering induction ports 18 and 19. The side wall of the font 12 is continued upwardly beyond the top 20 of the font as shown at 21, and is flanged outwardly as shown at 22 to provide a seat for the globe 13. Beyond the seat 22, the ring is flanged upwardly, 85 as shown at 23, to enclose the lower portion of the globe and at the upper margin of this latter flange, it is overturned as shown at 24 to rest upon and enclose the upper margin of the section 16 of the base ring. 90

The top plate 20 of the font is permanently secured within its side wall, as by crimping the latter as shown and the joint may be sealed with solder. The burner 25 is preferably seated within the top plate of the font by a slip joint and there is present the usual wick raising spindle 26 extending to the exterior of the base ring. 95

The upstanding flange 21 of the side wall of the font is provided with ports 27, preferably arranged as an annular series and 100

are disposed entirely above the top 20 of the font to provide for the uninterrupted admission of air currents and direct them toward the burner.

5 The font 20 is seated suspended within the lower or contracted portion of the base ring 11 and is stayed at its upper end by engagement of the flanges 23 and 24, with the upper margin of this ring, with which 10 it is held in engagement by the downward pressure of a spring within the dome, exerted thru the globe 13. The parts are easily assembled by swinging backwardly the dome 14, which, as is usual, will be hinged and 15 latched to the guard frame 10, and lifting out the globe 13.

While it has been common practice, as shown in the Hamm & Schuetz patent above referred to, to make the base ring of two 20 diameters, the two sections being united by a downwardly facing annular shoulder, and it has also been usual to pierce this shoulder to provide induction ports, it has been found that the flame is not infrequently extinguished by the jumping and running of the 25 user, above mentioned. This trouble has been overcome in the present invention by giving the shoulder 28, which unites the upper and lower sections of the base ring, 30 the form of undercut, the upper section 16 of the base ring extending slightly below the top of the lower section thereof. While the shoulder 28 is shown as straight in cross section, this configuration is not essential. The 35 induction ports 19 in the shoulder 28 may be as numerous and of such capacity as will be best suitable to the admission of an adequate air supply while guarding against violent wind currents. It is believed, though the 40 theory of the action which takes place may be a mistaken one, that the rapid vertical movement of the lantern when the user is running induces a reversal of currents within the body of the lantern by the rapid movement 45 of air currents across the ports 18 and past the lower margin of the upper section 16 of the base ring. It is further thought that a similar inductive action is set up by strong wind currents across the ports 19 50 when the shoulder 28 is flat. It is thought that the undercut form of shoulder herein shown results in an eddying action whether the external air currents be vertical or horizontal, causing an inflow of air thru the 55 ports 19 under all circumstances. By supporting the font upon the upper margin of the base ring and holding it to this seat by

spring pressure, movement of the font relatively to the base ring under the influence of jarring is prevented.

60 The details of the supporting connection for the font may be varied within the scope of the invention.

I claim as my invention:

1. In a signal lantern, in combination, a 65 base ring, and a font within the ring and having an outstanding flange forming a globe seat and loosely seated upon the upper portion of the base ring.

2. In a signal lantern, in combination, a 70 base ring, and a font within the ring and having an outstanding flange forming a globe seat and spring seated upon the upper margin of the base ring.

75 3. In a signal lantern, a font, a ported base ring, inclosing, extending above and spaced from the font to form therewith an air chamber, the side wall of the font being extended upwardly and ported and having at the upper end of such extension an outstanding flange forming a globe seat and resting upon the upper margin of the ring.

80 4. In a signal lantern, a base ring the upper portion of which is of greater diameter than its lower portion, the adjacent margins of the two portions overlapping and a ported web connecting such two portions and being connected with the lower portion above the lower margin of the upper portion.

85 5. In a signal lantern, in combination, a 90 base ring, a font seating within the ring, the upper portion of the ring being offset outwardly to inclose with the font wall, an air chamber, the web connecting the lower and upper portions of the ring being ported and upwardly offset, the side wall of the font being prolonged beyond its top and ported and at its upper margin flanged outwardly to form a globe seat and to engage the upper margin of the ring.

95 100 6. In a signal lantern, having a base ring, a font housed within the base ring, a globe and a dome, a globe seat carrying the font and resting upon the base ring and a spring within the dome urging the globe downwardly upon its seat.

105 7. In a signal lantern, in combination, a base ring, and a font suspended within the ring by a flange seated upon an upwardly facing portion thereof, and means pressing the flange to such seat.

In testimony whereof I affix my signature.

WILLIAM S. HAMM.
